[57] ABSTRACT

An electromagnet assembly for use in vehicle brakes having an operating arm in which the magnet housing is held on said arm by an attachment and retaining means consisting of a pair of holes spaced from the axial center pole of the magnet and a pair of fingers on the operating arm extended into the holes in the center pole. A round plastic keeper means is attached to the outer end of the finger in the hole nearest the trailing edge of the operating face of the magnet and forms a force transmitting means between the magnet and the finger and arm. The other finger and holes serve as an anti-rotational means, and the hole having the keeper means is provided with either a pair of opposed shoulders or an annular shoulder near the end of the hole opposite the operating face of the magnet to provide a restriction for the keeper means to retain the magnet in place on the fingers.

**ELECTROMAGNET OPERATING ARM
RETAINING MEANS IN A VEHICLE BRAKE
STRUCTURE**

In a conventional, hydraulically actuated brake, a pair of brake shoes are pivotally secured to a stationary brake back-up plate and are moved into contact with a brake drum by the actuation of a piston in a hydraulic brake cylinder responsive to fluid pressure applied to the brake cylinder. In an electrically actuated system, the brake shoes are moved by means responsive to an electrical current, such a system being exemplified by the U.S. Pat. to William F. Penrose, No. 2,273,065. In these electrically operative systems, a lever arm is pivotally secured to the brake back-up plate such that rotation of the lever arm causes movement of the brake shoes into contact with the brake drum. At the end of the lever arm is secured an electromagnet which is usually maintained in sliding contact with an armature plate which is secured to and moves with the brake drum. In a one piece cast iron drum and hub assembly, the face of the drum may serve as the armature plate. When the electromagnet is energized, it is magnetically attracted to the rotating armature plate, and, due to the friction between these two metal parts so attracted, a force is imposed on the magnet tending to move it in the direction of movement of the armature. This force is in turn transmitted by the lever arm to actuate the brake shoes into braking engagement with a brake drum.

In the present state of the art, brake electromagnets are generally attached to the brake shoe actuating arm as described in U.S. Pat. Nos. 2,273,065 or 3,244,259. As set forth in the first of these patents, it is desirable to mount the electromagnet non-rigidly on the lever arm from within the central portion of the electromagnet and at a plane closely adjacent that of the rubbing contact between armature and electromagnet in order to reduce the moments tending to overturn the electromagnet. This relationship helps to prevent the establishment of unequal pressures on the face of the electromagnet and hence helps to greatly minimize the production of localized high temperature and high pressure areas. It is also desirable to mount the electromagnet so that it has limited freedom of axial and universal pivotal movement with respect to the lever arm. If the armature in rotating tends to oscillate slightly in the axial direction due to end play, or to wobble or otherwise run out of true, the electromagnet can move in accommodation therewith, thereby tending to maintain the desired flat rubbing contact relationship between the electromagnet and armature faces. The moments tending to tip or overturn the magnet produce unequal pressures on the face of the magnet, and the resulting high pressure and high temperature areas of the magnet face are extremely detrimental to the braking performance and useful life of the magnet.

In operation, the brake electromagnet is mounted on the brake actuating arm and is maintained in a light pressure contact with the armature plate or drum face by spring pressure. When the electric brakes are applied, the magnet is energized and is magnetically attracted to the rotating armature. The magnet moves with the rotating armature until restrained by the brake actuating arm. The drum armature continues to rotate and generates extreme surface friction and heat at the face of the magnet. The tilting moments created at the point of restraint of the magnet by the actuating arm

impose an increased contact pressure on the leading edge of the magnet, i.e. the edge meeting the oncoming armature face, and a corresponding reduction of pressure on the trailing edge. This of course increases the friction and wear on the leading edge of the magnet. As the leading edge wears down, it forms a new tapered friction face plane from the leading edge to the point of actuating arm restraint, and in a relatively short time the trailing half of the magnet is not in contact with the armature. Hence, the braking effectiveness of the magnet is continuously reduced until complete failure occurs.

The present state of the art, in actual practice and as set forth hereinbefore, does not recognize another important factor of the magnet mounting design which also determines the magnitude of the moments tending to tilt or overturn the magnet toward its leading edge. This factor is the distance of the restraining force from the leading edge of the magnet. The moments of tilt imposed by the restraining force are reduced in direct proportion to an increase in the distance of the restraining force from the leading edge. Thus there are three basic design objectives in the mounting of the electromagnet to the actuating arm which must be achieved to improve the performance and extend the useful life of the electromagnet, namely: minimizing the distance of the restraining force from the frictional face of the magnet to reduce tilting moments, maximizing the distance of the restraining force from the leading edge of the magnet to reduce tilting moments, and minimizing the frictional locking tendency of the magnet on the actuating lever arm to insure that the magnet has the necessary freedom of movement required to maintain its full face in flat rubbing contact with the armature face.

In current practice, two basic systems of mounting the electromagnet on the actuating lever arm are employed. One system utilizes a pin or stud attached to the actuating lever arm and extending into a round hole in the center of the magnet core. The pin or stud has a spherical head which restrains the magnet while permitting sufficient universal movement of the magnet face. Another pin or projection extends from the actuating lever arm into and through an outboard lug or projection which protrudes from the outer periphery of the magnet near the side opposite the friction face. This is used to prevent rotation of the magnet and has a restraining clip or pin to retain the magnet on the actuating lever arm. While unnecessary tilting moments are created by the location of the restraining force and the anti-rotational lug, one of the major disadvantages of this system is the expensive construction of the actuating lever arm and the magnet.

The other mounting system in use employs a rectangular restraining arm inserted in a rectangular hole in the core of the magnet. The rectangular restraining arm in a rectangular hole prevents rotation of the magnet and also serves to retain the magnet on the lever arm by use of a retaining pin through a hole in the arm and an accommodating slot recessed in the face of the magnet core. This system is less expensive; however, to gain this advantage the tilting moments were increased by moving the point of the lever arm restraining force considerably closer to the leading edge of the magnet, and replacing the smooth spherical surface which restrained the lever arm by sharp steel edges which tend to lock the magnet in one position when subjected to

the restraining and twisting forces imposed on the magnet.

It is therefore one of the principal objects of the present invention to provide a magnet and lever arm attachment means which will greatly increase the performance and useful life of the electromagnet, and which is relatively simple in construction and operation, resulting in optimum performance of the magnet and arm in the braking operation.

In the present invention, the object of increasing the performance and useful life of the electromagnet by improving and simplifying the attachment, retention and operating relationship of the electromagnet to the brake actuating arm is accomplished by: applying the restraining force as close to the magnet friction face as possible, thus reducing the tilting moments; moving the restraining force away from the leading edge of the magnet as far as operating clearances permit, much farther than is current practice, thus further reducing the tilting moments; restraining the magnet by a spherical bushing of plastic with a relatively low coefficient of friction, such as nylon, thus avoiding frictional lockup.

Further objects and advantages of the present invention will become apparent from the following description and accompanying drawings, wherein:

FIG. 1 is an elevational view of a backing plate, brake shoe and operating mechanism of the type which may be used in combination with my electromagnet attachment and retaining device;

FIG. 2 is a cross-sectional view of an electromagnet embodying the present invention, the section being taken on line 2—2 of FIG. 1;

FIG. 3 is an elevational view of the operating lever arm of the brake shown in the preceding figures;

FIG. 4 is an edge elevational view of the lever arm shown in FIG. 3, as viewed from the position indicated by line 4—4;

FIG. 5 is a fragmentary edge elevational view of the lever arm;

FIG. 6 is an exploded perspective view of an electromagnet and the attachment device for securing the magnet to the lever arm;

FIG. 7 is a plan view of a portion of the attachment device shown in FIG. 6;

FIG. 8 is a cross-sectional view of the part shown in FIG. 7, the section being taken on line 8—8 of the last figure;

FIG. 9 is a cross-sectional view of a modified form of the parts shown in FIGS. 7 and 8;

FIG. 10 is a plan view of the part shown in FIG. 9;

FIG. 11 is a plan view of the magnet;

FIG. 12 is an elevational and fragmentary cross-sectional view of the magnet shown in FIG. 11;

FIG. 13 is a fragmentary cross-sectional view taken on line 13—13 of FIG. 12; and

FIGS. 14 and 15 correspond to FIGS. 11 and 12 but illustrate a modified form of the attachment structure.

Referring more specifically to the drawings and FIG. 1 in particular, numeral 10 indicates generally the brake assembly, including a brake operating mechanism 12 and a brake drum 14 which is attached to and normally forms a part of the wheel structure of the vehicle in which the brake is used. The brake assembly includes a backing plate 16 on which brake shoes 18 and 20 are pivotally mounted and movably secured thereto or restrained by spring-loaded retaining pin as-

semblies 22 and 24, respectively. The brake shoes contain friction material 26 and 28 bonded to the external surface of the brake shoes, and engage the internal surface of drum 14 when the brake is applied. An adjustment screw 30 interconnects the brake shoes, which are yieldably retained in their retracted position from the brake drum by springs 32 and 34.

The brake actuating mechanism for applying brake shoes 18 and 20 into braking engagement with the 10 drum consists of an electromagnet 40, a lever 42 connected at one end to the magnet and pivotally mounted on a pin 44, which in turn is secured to backing plate 16. Lever 42 swings on pin 44 and is curved in an offset manner to pass around the drum axis and to position the electromagnet at a point 180 degrees from pin 44. 15 Arm 42 includes an extension or short arm 46 carrying a pin 48 on a swivel block 50, which bears against the adjacent ends of the brake shoes. The magnet is operated in conjunction with a radially positioned armature 20 51 connected directly to or forming an integral part of brake drum 14, on a plane parallel with backing plate 16. The magnet 40 is adapted to frictionally engage the face of the armature when energized and is mounted on arm 42 by an attachment and retainer means 55 described more fully hereinafter. A coil spring 57 reacting between lever 42 and the magnet urges the magnet into light pressure contact with the armature.

The magnet attachment and retainer means 55, best 25 shown in FIGS. 2 and 6, consists of finger 60 and finger 30 62 joined integrally at a right angle to lever 42 and extending into holes 64 and 66, respectively, in the center pole of magnet 40. A force transmitting bushing 70, which is secured to the end of finger 60 and retains the magnet on the fingers, fits freely in hole 64 with only 35 the spherical diameter of the bushing contacting the cylindrical wall of the hole as near as practical to the frictional face of the magnet. This design minimizes tilting moments while permitting smooth, friction free, limited universal movement of the magnet. The two holes 40 64 and 66 are offset in opposite directions from the axis of the center pole 68, with hole 64 being offset in the direction of the trailing edge of the magnet housing for minimizing uneven wear of the magnet face as explained hereinbefore.

45 Round restraining hole 64 is located off center toward the trailing edge of the magnet, thus permitting the anti-rotational hole 66 to be in the center core rather than on the outer periphery of the magnet as in some present brakes. Bushing 70 and finger 60 transmit the force created between the armature and the magnet to arm 42 for actuation of the brake, while finger 62, in round hole 66, prevents any substantial rotation of the magnet on its center axis. The two fingers 60 and 62 are preferably formed as an integral part of the actuating lever 42, and added strength is gained at the right angle bend by web 79 connecting the two fingers. The upper end of finger 60, as viewed in FIGS. 2, 4 and 6, contains a pair of opposed slots 72 and 74 which grip the inner wall 76 of bushing 70 when the bushing is 50 pressed onto the free end of finger 60, in the manner illustrated in FIG. 2, thus releasably locking the bushing in place on the end of finger 60. In order to retain the magnet 40 on fingers 60 and 62 when the brake drum and armature are not in place, shoulders 77 and 78, as shown in FIG. 11, are provided at the lower edge of hole 64 which require the compression of ribs 82 and 84 of bushing 70, as shown in FIGS. 7 and 8, in order 55 60 65

for it to pass between the shoulders. This relationship retains the magnet on the fingers while at the same time permitting the magnet to be disassembled from the fingers by forcing the magnet away from lever 42 and forcing bushing 70 through the lower end of hole 64 between the two shoulders 77 and 78.

A modification of the hole is illustrated in FIGS. 14 and 15, which consists of a single annular shoulder 80 for retaining the magnet on the two fingers, the hole defined by shoulder 80 being large enough to permit finger 60 to easily pass therethrough, but being sufficiently restricted to prevent bushing 70, or a modified form of bushing 70' as shown in FIGS. 9 and 10, from slipping from hole 64, thus retaining the magnet on the fingers and requiring removal of the bushing from finger 60 before the magnet can be removed from arm 42. Bushing 70' is fully circular and contains a center recess 88 for receiving the upper end of finger 60, and a portion having a spherical diameter near the upper end, i.e. adjacent the friction face of the magnet. Both bushings 70 and 70' are preferably made of low friction, high density plastic material.

In a simple and rapid assembly operation, compression spring 57 is affixed to the lever arm encircling the two upright fingers which serve as a guide to maintain the spring in a central concentric position against the magnet. The magnet is placed over the two fingers so that the two fingers extend through their mating holes in the magnet. The plastic drive bushing 70 or 70' is pressed into position over the end of finger 60, completing the assembly operation of the magnet and arm. As mentioned previously, the plastic drive bushing serves to retain the magnet to the lever arm as well as transmit the braking force from the magnet to arm 42. As previously mentioned, the round hole 64 in the magnet is restricted at the end opposite the friction face to prevent passage of the drive bushing and this restriction may take the form of a smaller round hole or protruding flat shoulders. To disassemble the magnet from the actuating arm, the arm is held down with one hand and a firm jerk on the magnet releases it from the actuating arm.

In positioning the plastic restraining and force transmitting bushing in a relatively close position to the face of the magnet and hence close to the armature, and in offsetting restraining hole 64 and finger 60 toward the trailing edge of the magnet face, tilting moments are minimal and uneven wear of the contact surface of the magnet is eliminated or minimized so that the full effectiveness of the magnet face is always available for the braking operation. Further, by locating the anti-rotational hole 66 and finger 62 in the center pole of the electromagnet rather than in an outboard peripheral lug, both the magnet and actuating arm are simplified and less expensive to fabricate. The new plastic force transmitting bushing 70, or 70', with its low friction spherical restraining surface, smoothly transmits the force created between the armature and the magnet to arm 42 to actuate the brake. This bushing also assures a smooth, friction free, limited universal movement of the magnet which is necessary to maintain its flat, rubbing relationship with the drum armature. Finally this force transmitting bushing 70 serves to retain the magnet on the actuating arm when the brake drum and armature are not in place.

While only one embodiment of the present magnet and arm structure has been described in detail herein,

together with several modifications, various other changes and modifications may be made without departing from the scope of the invention.

I claim:

- 5 1. An electromagnet assembly for use in electric vehicle brakes having an operating arm, comprising a housing having a center pole and a peripheral pole and an annulus therebetween, said center pole having a pair of holes, fingers on the actuating arm each extending into one of the holes in said center pole, and retaining means secured to one of said fingers for transmitting the force from said magnet to said arm and for retaining the magnet on said fingers.
- 10 2. An electromagnet assembly for use in electric vehicle brakes as defined in claim 1 in which said holes in said center pole are both round and are spaced from the axial center of the housing of said electromagnet.
- 15 3. An electromagnet assembly for use in electric vehicle brakes as defined in claim 1 in which said hole receiving said retaining means is offset from the center axis of said pole in the direction corresponding to the trailing edge of the face of said housing.
- 20 4. An electromagnet assembly for use in electric vehicle brakes as defined in claim 3 in which the other of said fingers serves as an anti-rotational means for the magnet and the hole therefor is offset from the center axis toward the leading edge of the face of the housing.
- 25 5. An electromagnet assembly for use in electric vehicle brakes as defined in claim 1 in which said retaining means has a spherical portion and said spherical portion contacts the cylindrical wall of the hole in close proximity to the friction face of the magnet.
- 30 6. An electromagnet assembly for use in electric vehicle brakes as defined in claim 1 in which a coil spring reacts between said magnet and said arm for urging said magnet away from said arm into operating position.
- 35 7. An electromagnet assembly for use in electric vehicle brakes as defined in claim 5 in which said hole receiving said retaining means is larger than said other hole and said other hole is offset from the axial center of said coil of said center pole in the direction toward said forward edge of the magnet housing.
- 40 8. An electromagnet assembly for use in electric vehicle brakes as defined in claim 7 in which the finger receiving the retaining means is larger than the other of said fingers.
- 45 9. An electromagnet assembly for use in electric vehicle brakes as defined in claim 1 in which fingers are joined integrally to the operating arm.
- 50 10. An electromagnet assembly for use in electric vehicle brakes as defined in claim 1 in which a web interconnects said fingers adjacent the lever arm.
- 55 11. An electromagnet assembly for use in electric vehicle brakes as defined in claim 1 in which said retaining means is round and contains a hole therein for receiving the respective finger and said finger contains a recess for receiving and securing said retaining means when placed on the end of one of said fingers adjacent the operating face of the magnet.
- 60 12. An electromagnet assembly for use in electric vehicle brakes as defined in claim 1 in which said hole for receiving said retaining means has a pair of opposed shoulders near the end of the hole opposite the operating face of the magnet.
- 65 13. An electromagnet assembly for use in electric vehicle brakes as defined in claim 1 in which said hole for

receiving said retaining means has an annular shoulder near the end of the hole opposite the operating face of the magnet.

14. An electromagnet assembly for use in electric vehicle brakes as defined in claim 1 in which said retaining means is constructed of low friction, high density material.

15. An electromagnet assembly for use in electric vehicle brakes as defined in claim 14 in which said retaining means has a peripheral portion with a spherical diameter.

16. An electromagnet assembly for use in electric ve-

hicle brakes as defined in claim 1 in which the hole receiving said retaining means has opposed shoulders near the end thereof spaced from the friction face of the magnet and said retaining means is provided with opposed yieldable bosses for passing between said shoulders.

17. An electromagnet assembly for use in electric vehicle brakes as defined in claim 13 in which the hole receiving said retaining means has an annular shoulder forming a restriction therein in spaced relation to the friction face of the magnet.
